UNITED STATES PATENT OFFICE.

HJALMAR TORGERSEN, OF ASHBY, MINNESOTA.

TOOTH FOR HAY-RAKES.

1,104,020.

Specification of Letters Patent. Patented July 21, 1914.

Application filed January 11, 1913. Serial No. 741,552.

To all whom it may concern:

Be it known that I, HJALMAR TORGERSEN, a citizen of the United States, residing at Ashby, in the county of Ottertail and State 5 of Minnesota, have invented a new and useful Tooth for Hay-Rakes, of which the following is a specification.

This invention relates to hay rakes and more particularly to teeth therefor, the same 10 being designed especially for use in connection with hay rakes such as shown, for example, in Patent 1,001,904, issued to me on August 29, 1911.

One of the objects of the invention is to 15 provide a spring tooth so constructed that, when a number of teeth are connected to the same supporting bar, any one of said teeth is free to spring upwardly, when striking an obstruction, without producing a corresponding movement of the remaining teeth.

A further object is to provide a spring tooth which will yield readily and which is so shaped as to prevent hay or the like from working up against the supporting bar or 25 against the rearwardly extending portion of the tooth and clogging the rake.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 30 the scope of what is claimed, without departing from the spirit of the invention.

In the accompanying drawings the preferred form of the invention has been shown.

In said drawings: Figure 1 is a front elevation of a portion of a bar having a series of teeth attached thereto. Fig. 2 is a section on line A—B Fig. 1. Fig. 3 is a plan view of the structure shown in Fig. 1.

Referring to the figures by characters of reference 1 designates the downwardly and forwardly curved back portion of the tooth the same being formed of stiff spring wire and provided at its lower end with an upwardly extending curved finger 2, this finger 45 curving backwardly and thence forwardly and gradually diverging from the back portion of the tooth. The upper end of the portion 1 merges into a loop or eye 3 and from this eye extends a forwardly project-

ing arm 4 the front of which merges into a 55 coil 5. This coil has a terminal eye 6 which may be engaged by a pin 7 or other suitable holding device engaging a rod 8 or other structure extended loosely through the coil 5.

It is to be understood that a series of these 60 teeth may be mounted upon the rod 8 or other supporting structure provided and, when the rake is drawn forward, the hay or other material being gathered will press against the finger 2 and, as this finger is 65 curved upwardly and forwardly toward the coil 5, it will be seen that the material will be prevented from packing against the arm 4 and will be rolled forwardly. Furthermore, as the entire device is made of a single 70 length of spring wire, it will be seen that should one of the teeth strike an unyielding obstruction, the said tooth can spring upwardly and backwardly without elevating the other teeth, this being permissible in 75 view of the fact that the arm 4 of the tooth will yield under such conditions.

What is claimed is:—

The combination with a supporting structure, of a tooth formed in a single length of 80 spring wire and including an arm extending rearwardly from said structure said arm having a coil at its forward end, said coil extending loosely around the supporting element and terminating in an eye, means extending through the eye and from said supporting element for holding the coil against rotation upon said element, a single loop at the other end of the arm, a downwardly and 85 forwardly curved projecting yielding portion extending from the loop, and a bowed finger extending upwardly from the lower end of said downwardly extending portion and terminating close to and below said supporting structure and below the coil, the 90 downwardly curved extending portion of the tooth passing adjacent the side of the arm and all parts of the tooth from the eye to the free terminal of the finger being free to yield in any direction when subjected to pressure. 100

In testimony that I claim the foregoing as my own, I have hereto affixed my signature in the presence of two witnesses.

HJALMAR TORGERSEN.
